UNITED STATES PATENT OFFICE

CARL L. CAPPEL, OF OAKWOOD, OHIO

DESIGN FOR A REMOVABLE SPORT TOP FOR AUTOMOBILES

Application filed September 10, 1931. Serial No. 41,054. Term of patent 7 years.

To all whom it may concern:

Be it known that I, CARL L. CAPPEL, a citizen of the United States, residing in the city of Oakwood, in the county of Montgomery and State of Ohio, have invented a new, original, and ornamental Design for a Removable Sport Top for Automobiles, of which the following is a specification, reference being had to the accompanying drawings, forming part hereof.

Figure 1 is a perspective view of a removable sport top for automobiles and Figure 2 is a rear perspective view of said removable sport top, showing my new design.

I claim:

The ornamental design for a removable sport top for automobiles, as shown.

CARL L. CAPPEL.
